REFRIGERATION CHARGING AND
EVACUATION APPARATUS

Ralph W. Doeg, Detroit, Mich., assignor to Nash-Kelvinator Corporation, Detroit, Mich., a corporation of Maryland

Application March 27, 1946, Serial No. 657,565

3 Claims. (Cl. 62—115)

1
This invention relates to refrigerating apparatus, and, more particularly, to the evacuation of fluids from refrigerating systems and the charging of refrigerants and lubricants into said systems.

One of the objects of my invention is to provide an improved arrangement and method for evacuating fluids from a refrigerating system.

Another object of my invention is to provide an improved arrangement for charging refrigerants and lubricants into refrigerating systems.

Another object of my invention is to provide an improved arrangement for evacuating air and moisture from a refrigerating system wherein such fluids are withdrawn from the high and low pressure sides of the system simultaneously.

Further objects and advantages will be apparent from the following description, reference being had to the accompanying drawings, wherein a preferred form of the invention is clearly shown.

The figure in the drawing illustrates a refrigerating system including an improved arrangement for evacuating and charging the system embodying features of my invention and shows the system partly diagrammatically and partly in cross section.

In refrigerating systems of the compression type now in general use it is common practice to control the flow of liquid refrigerant from the condenser to the evaporator by a capillary or small diameter tube. The tube offers the necessary resistance to allow only the proper amount of liquid to flow into the evaporator. Such systems include so-called high and low pressure sides. The high pressure side of the system extends from the discharge side of the compressor through the condenser to the capillary tube. The low pressure side of the system extends from the outlet of the capillary through the evaporator to the inlet of the compressor.

In manufacturing systems of the aforesaid type, it is customary to evacuate all air and moisture from the system before charging the system with refrigerant and lubricant. In evacuating such fluids from the system a partial vacuum is produced therein. In the event a device is connected to the system on the low pressure side to evacuate the system it would be necessary to withdraw the fluids on the high pressure side through the capillary tube which offers considerable resistance and the result is that it requires a considerable length of time to evacuate the system.

In accordance with my invention, I provide an

2
arrangement for quickly evacuating a refrigerating system. By my invention I evacuate both the high and low pressure sides simultaneously thereby eliminating the necessity of drawing all of the fluid from one side of the system through the capillary tube.

Referring now to the drawings, the numeral 20 designates, in general, a motor compressor unit, preferably like the unit shown in the patent to Lawrence A. Philipp, No. 2,199,415, issued May 7, 1940. This type unit shown in the patent includes a motor and a compressor enclosed in a sealed casing with the interior of the casing being on the low pressure side of the system and the discharge side of the compressor being in open communication with the condenser on the high pressure side of the system. The unit 20 herein shown includes a sealed casing 22 which encloses a motor compressor unit 23. The casing 22 provides a chamber or crankcase 24 which is on the low pressure side of the system and is in open communication with the intake of the compressor. The compressed refrigerant is not permitted during operation of the compressor to enter the interior of the casing 22 and is conducted outside of the casing through a conduit 26 and a combination evacuating and charging valve 30. The conduit 26 is connected to the discharge outlet of the compressor and conducts the compressed refrigerant directly to the interior of valve 30. The compressed refrigerant after passing through valve 30 passes through conduit 34 into a condenser 36 wherein it is liquified and from which it passes through a strainer 38 to a capillary or small diameter tube 40. The tube 40 offers considerable resistance and during operation of the compressor the tube maintains the pressure on the high pressure side of the system somewhat above the pressure on the low pressure side of the system. The high pressure side of the system extends from the discharge side of the compressor to the tube 40. The liquified refrigerant, after leaving the tube 40, flows into evaporator 44, wherein it is evaporized and from which it flows through vapor return conduit 46 into the crankcase 24 which is in open communication with the intake of the compressor. The refrigerant, after leaving tube 40, enters the low pressure side of the system, which extends through the evaporator 44, conduit 46 and crankcase 24 to the intake of the compressor.

The valve 30 includes a main valve casing 50 which extends through and is affixed to the casing 22. The casing 50 is provided with horizontal passages 54, 56, 58 and 60. The casing 50 is also

provided with a vertical passage 64. A hollow fitting 66 connects conduit 26 to passage 64. Thus discharged refrigerant leaving the compressor outlet is free to flow into conduit 34 through conduit 26, hollow fitting 66, passages 54, 56, 64, 58 and 60.

A flanged metal cup 70 extends downwardly in the upper part of passage 64. A metal plug 72 is inserted into the upper part of cup 70. The casing 50, cup 70 are brazed together to provide air tight joints. Within the plug 72 extends a set screw 76 with the lower part arranged for engagement with the flat part of cup 70.

Within the lower part of casing 50 and extending into passage 64 is a plug member 80. The plug member 80 is provided with a vertical passage 82 and a horizontal passage 84 in open communication with passage 82. Surrounding the upper part of passage 82 in plug 80 is an annular valve seat 90 which is adapted to receive the bottom part of cup 70 when such bottom part is depressed by movement of set screw 76. When this takes place the upper part of passage 82 is sealed by cup 70. The plug 80 is brazed in casing 50 to provide an air tight joint.

The horizontal passage 84 in plug 80 is in open communication with a passage 100 provided in casing 50. The passage 100 is in open communication with the interior of the casing 24 and the low pressure side of the system.

Inserted in the lower part of plug member 80 is a screw threaded hollow valve member 104. The member 104 includes a tapered valve proper 106 which protrudes into the lower end of passage 82 for sealing the lower end thereof. The valve member 104 is hollow as at 108 and includes an angular passage 110 arranged so that the lower end is in open communication with the hollow portion 108 and the upper end of passage extends through the edge of the tapered valve proper 106. Within the hollow part 108 of valve member 104 are notches 112 for receiving any suitable tool for rotating valve 104.

A suitable tool for rotating valve 104 is the tool 120 which is carried in a hollow housing 124 secured to plug 80 by coupling 125. The housing 124 includes vertical passages 126, 128 and 130. A snap on type of hollow fitting 132 is secured to housing 124 and is in open communication with passage 130. The tool 120 is operated by wheel 134 and may be pushed into notches 112 by pushing the wheel toward the housing 124 against the action of a return spring 136. When tool 120 is received in notches 112 the tool 120 may be rotated by rotation of wheel to rotate valve 104.

When the system is completed and it is desired to evacuate the system of air and moisture, a vacuum producing device 137 is attached to fitting 132. The valve 104 is then unscrewed partially so that valve proper 106 is spaced below passage 82 so that upper end of passage 110 is in open communication with passage 82. When the vacuum producing device 137 begins operation the air and moisture are evacuated from the high pressure side of the system, through condenser and conduit 34 into passage 60 and passage 58 into passage 64 and from the discharge side of the compressor through conduit 26, fitting 66, passages 54 and 56 into passage 64. Further evacuation from the high pressure side continues through passages 82, 110, 108, 126, 128 and 130 and fitting 132. Evacuation from the low pressure side of the system is through evaporator 44, conduit 46, interior of casing and intake side of

compressor into passage 100. Evacuation from passage 100 is through passages 84, 82, 110, 108, 126, 128 and 130 and fitting 132. When this evacuation takes place, both ends of the tube 5 40 are being drawn on through the high and low pressure sides of the system simultaneously and it is unnecessary to evacuate the air and moisture from one side of the system through the small diameter tube 40.

10 When the system is evacuated the set screw 16 is turned to force the flat part of cup 70 into engagement with seat 90 to seal the entrance into passage 82 from passage 64. The valve 104 is then rotated by tool 120 so that valve proper 106 seals the lower end of passage 82 to maintain the partial vacuum produced in the system. The vacuum producing device 137 is then removed from fitting 132 and a source of refrigerant and oil connected thereto to charge the system. Any suitable refrigerants and lubricants may be introduced into fitting 132. After the charging sources are connected to fitting 132 the valve 106 is moved away from passage 82 by tool 120 to allow the charge to enter the low pressure side of the system. The charge enters the low pressure side of the system through fitting 132, passages 130, 128, 126, 108, 110, 82, 84 and 100 into crankcase 24, and is in open communication with the intake of the compressor. The valve 106 is again moved after the charge is complete so that valve 106 seals the lower part of passage 82. The coupling 125 and housing 124 may then be removed from plug member 80. With cup 70 sealing the inlet of passage 82 and valve 106 sealing the outlet of passage 82 the system is ready for operation. During operation the refrigerant leaves the compressor through conduit 26 whence it passes through casing 50 into conduit 34 and into the condenser. From the condenser the liquid flows through strainer 38, tube 40 into evaporator 44. The evaporated refrigerant leaves the evaporator 44 through vapor return conduit and flows into the interior of crankcase 24 and into the intake side of the compressor. When coupling 125 and housing 124 are removed a suitable closure may be placed over the lower end of plug 80, to keep dirt and other particles out of the passages 108 and 110.

50 Although only a preferred form of the invention has been illustrated, and that form described in detail, it will be apparent to those skilled in the art that various modifications may be made therein without departing from the spirit of the invention or from the scope of the appending claims.

I claim:

1. A refrigerating system comprising a high pressure portion and a low pressure portion, an elongated orifice connecting said portions having a passage interposed in said high pressure portion, a second passage connecting said first passage and said low pressure portion and a charging port in said second passage, a valve member controlling said port, means for evacuating fluids from said portions simultaneously by withdrawing said fluids in opposite directions away from said elongated orifice and a manually operable valve for controlling flow between said passages.

60 2. Refrigerating apparatus comprising a motor compressor unit, a condenser, a refrigerant evaporator, means providing passageways directly from the outlet of the compressor to the inlet of the condenser and to the inlet of the compressor without extending through the evaporator a valve member for closing the passageway from

the outlet of the compressor directly to the inlet of the compressor, a port in said last mentioned passage for withdrawing refrigerant, and a manually operable valve member controlling said port.

3. Refrigerating apparatus comprising a casing, a compressor in said casing, a condenser, a refrigerant evaporator connected to the outlet of said condenser and to said casing, conduit means connected to the outlet of the compressor and the inlet of said condenser, additional conduit means connected in open communication with said first named conduit means and said casing, means for withdrawing air through said additional conduit means from said condenser, casing and evapo-

rator, a manually operable valve member controlling flow through said additional conduit means, and a second manually operable valve member controlling flow between said conduit means and said additional conduit means.
